UNITED STATES PATENT OFFICE.

CORNELIS WILHELM SNELLEBRAND AND JOSÉ PINTO RODRIGUES DE
BRITTO, OF RIO JANEIRO, BRAZIL.

APPLIANCE FOR CLEANING FLOORS, WALLS, WINDOWS, &c.

SPECIFICATION forming part of Letters Patent No. 701,637, dated June 3, 1902.

Application filed August 8, 1901. Serial No. 71,394. (No model.)

To all whom it may concern:

Be it known that we, CORNELIS WILHELM SNELLEBRAND, a subject of Her Majesty the Queen of the Netherlands, and JOSÉ PINTO RODRIGUES DE BRITTO, a citizen of the Republic of Brazil, both residing at Rio Janeiro, Brazil, have invented a certain new and useful Improved Appliance for Cleaning Floors, Walls, Windows, and the Like, of which the following is a specification.

Our invention consists of an improved appliance for cleaning and hygienic purposes to replace brooms and feather brushes, its object being to enable the interiors of houses to be effectively cleaned by removing and dissolving the dirt and dust thereof and by catching and retaining (until removed) disease germs of all kinds. The appliance, which we term a "hygienic broom," is capable of far more extended application than the older appliances and may be used for cleaning floors, doors, windows, ceilings, walls, window-glass, carpets, pictures, glass, furniture, and the like. The appliance will maintain a high state of cleanliness in houses and obviate the need of washing down with large quantities of water, frequently a disagreeable and damaging operation.

Sponge, as being flexible and porous, owing to which it can take up water where desired, is the material employed as the principal agent in the appliance. A very simple arrangement enables the impurities to be easily removed and permits the dust and micro-organisms deposited on the surfaces in question to be collected in an efficacious manner.

Different modifications of our invention are illustrated in the accompanying drawings, in which—

Figure 1 is a side elevation of the appliance. Fig. 2 is a front elevation. Fig. 3 is a side elevation showing an incorrect manner of using the appliance. Fig. 4, on a reduced scale, shows the broom applied to the cleaning of vertical surfaces; and Fig. 5, the same for horizontal surfaces, while Figs. 6 and 7 represent a modified form specially intended for cleaning the floor underneath heavy articles of furniture and showing two positions of the appliance.

The appliance is constructed of two un-

equal-sized plates *a b*, which may be pieces of wood, as shown, which are connected one to the other by means of two steel springs *c*, and thereby firmly clip the sponge *d*. The handle *e* is attached to the center of the larger piece *a*. Figs. 4 and 5 differ only in the method of attaching the handle *e* to the piece *a*, according as the broom is to be used for vertical or horizontal work.

The appliance is easy and convenient to handle. The sponge, being steeped in water or in an antiseptic solution until all the air is driven out of the pores and then squeezed to remove the excess of liquid, is placed in the appliance in such a manner that about one-third of the sponge overlaps the wood, thus forming a swab which will come in contact with the surfaces to be cleaned. All that is then necessary is to slowly pass the appliance over whatever article is to be cleaned, only a very slight pressure being applied by the hand resting on the handle. For cleaning carpets, pictures, and other things which it is undesirable to damp the sponge is used in a moist state, but nearly free from water. When the sponge is dirty, it is washed in a pail of water without removing it from the handle, simple immersion followed by squeezing out by hand several times repeated being sufficient.

The appliance should always be moved in one direction—namely, drawn toward the user—this being evidently essential when the removal of dust and disease germs is in question. This mode of application is indicated by the construction of the appliance, since if moved in the other direction the pressure of the springs *c* will be overcome, the piece *b* then separating from the piece *a*, and the sponge being released, thus interrupting the work. Fig. 1 shows the right way to use the appliance, while Fig. 3, illustrating the reverse movement, shows that the sponge is no longer held fast and will escape. In order to properly use the appliance, therefore, it is necessary to lay the same on that part of the floor or other surface to be cleaned that is farthest away from the operator and to then draw it inward, allowing it to slide over the surface. For floor-cleaning an ordinary sponge is used, but a finer-quality sponge

must be taken for cleaning curtains, ceilings, mirrors, pictures, &c.

The handle *f* (shown in Figs. 6 and 7) takes the form of a bent stick, a small roller *g* being attached at the bend or elbow to support the broom when the appliance is pushed outward, a slight pressure of the hand on the other extremity of the handle keeping the sponge from touching the floor, as shown in Fig. 6. On the other hand, while the broom is being drawn toward the operator the handle is lifted, thus raising the roller out of contact with the floor, as shown in Fig. 7.

Compared with ordinary brooms or brushes,
15 our appliance offers the following advantages:

(a) The practical manner in which surfaces can be cleaned with water by dissolving and immediately absorbing dirt, dust, and taking up micro-organisms, which latter would otherwise be disseminated through the atmosphere of the house.

(b) Its general utility, enabling all the internal surfaces of a house to be cleaned. It does not injure any material. On the contrary, the fabrics used for making carpets, curtains, &c., preserve their primitive freshness.

(c) Its use has the advantage of combining the cleaning and disinfection of the house in one operation. It is an efficient prophylactic and enables the use of destructive compressed-air pumps to be dispensed with.

(d) Its mechanical arrangement, the result of the different resistances of the two parts

holding the sponge, necessitates the broom 35 being worked in the direction requisite to insure proper hygienic and efficacious cleaning, any movement in the opposite direction being prevented by the apparatus itself.

What we claim is—

1. In an appliance of the character described, a pair of plates, a spring connection secured to said plates for forcing them one toward the other, an absorbent material adapted to be arranged between the said plates and held in position by the action of the spring connection, and a handle connected to one of the said plates.

2. In an appliance of the character described, a pair of plates, a spring connection secured to the said plates and adapted to force one toward the other, an absorbent material arranged between said plates and retained in position by the action of said spring connection, a handle connected to one of said plates and having a portion thereof extending at an obtuse angle to the remaining portion, and a roller connected to the handle at the jointure of the angularly-disposed portion of the handle with the remaining portion thereof. 55 60

In testimony whereof we have hereunto set our hands in the presence of two subscribing witnesses.

[L. S.] CORNELIS WILHELM SNELLEBRAND.
JOSÉ PINTO RODRIGUES DE BRITTO.
